PORTABLE FOAM PRODUCING APPARATUS

Filed Sept. 28, 1927

UNITED STATES PATENT OFFICE

JAMES A. McCACKEN, OF LOS ANGELES, CALIFORNIA

PORTABLE FOAM-PRODUCING APPARATUS

Application filed September 28, 1927. Serial No. 222,635.

- The art of extinguishing fires in general, and particularly oil fires, by means of "Foamite" or "Firefoam" is very well known and understood. It consists in bringing into admixture solutions of (a) aluminum sulfate and (b) hydrogen sodium carbonate and a substance having the property of increasing the surface tension of aqueous liquids, such for instance as glue or licorice. By the admixture of said solutions in proper proportions a very dense and tenacious foam is produced which, as it consists mainly of water, is a highly efficacious and valuable agent for extinguishing fires.
- For reasons which it is not necessary to elaborate here the foam itself cannot be pumped through a line for any great distance, and it is therefore requisite to bring the solutions together at or near the seat of the fire.
- Where large installations such as oil tank farms are to be protected, it is customary to install separate tanks and pumps for the two solutions and separate pipe lines for the distribution of the solutions over the area to be protected, but as this calls for a heavy initial investment it is common practice to take care of smaller needs by means of portable extinguishers.
- Heretofore these portable extinguishers or "Foamite carts" have consisted of a single tank mounted on light running gear, the whole being of such weight as to be manipulated by one or two men. Inside the apparently single tank referred to is placed a smaller tank of less capacity, the smaller tank being filled with one of the solutions while the space between the two tanks contains the other. An inside valve operated from the outside establishes a connection between the two bodies of liquid, the carbon dioxide generated by the reaction creates a high pressure within the system, and the foam is thus forced out through an opening in the outer tank and through a hose to the seat of the fire.
- This arrangement, while simple and convenient, has two very serious disadvantages. The first is that the pressure created within the tank and the high velocity at which the foam is discharged tend to break down the foam and greatly reduce its volume. This
- tendency manifests itself to such an extent that whereas properly proportioned foam solutions should increase in volume ten times, that is, one volume of the combined foam solutions should produce ten volumes of foam, the actual increase in volume in the portable tank apparatus is seldom more than three to one. The second is the very limited capacity of an apparatus of such size as to be truly portable. For instance, a tank cart such as above described, having a nominal capacity of forty gallons but actually charging only thirty-three gallons of solutions, would have a discharge capacity of 33×3 or 100 gallons of foam. This small quantity of foam will take care of but a trifling fire, and as the apparatus requires some time to recharge, its range of usefulness will obviously be extremely limited.
- The object of my invention is to provide a portable unit weighing approximately half as much as a charged forty gallon tank extinguisher, which will give an absolutely continuous and uninterrupted stream of foam which may be kept constant over a rather wide range of controlled variation, and which at its normal or average operating rate will yield one thousand gallons of foam, or ten times the total capacity of a forty gallon tank extinguisher, every minute of its operation.
- The usefulness and many further advantages of my invention will be apparent from an inspection of the attached drawings and the following description thereof. In these drawings, which illustrate a preferred application of my invention:
- Figure 1 is a plan drawing of the assembled apparatus.
- Figure 2 is a side elevation of the assembled apparatus with one wheel of the cart removed.
- Figure 3 is an end elevation of the assembled apparatus.
- Figure 4 shows, in interior elevation, one of the mixing and dissolving units indicated at 1^a—1^a—1^b—1^b in Fig. 1, four of such units being used in the complete apparatus.
- Figure 5 shows in interior elevation a preferred type of valve for use between the mixer 2 and the dissolver 3 as shown in Fig. 4.

Figure 6 shows in interior elevation the supporting plate which may advantageously be used in the mixing vessel 2 shown in Fig. 4.

Referring to Figs. 3 and 4, the four units 1^a and 1^b are supported on a substantial axle 4, supported in turn by the two wheels 5—5, the whole forming a rigid unit capable of being easily moved. A relatively light handle 6 is attached to this unit to afford a handhold for one or two men, one being quite sufficient unless the machine is being handled over very soft or rough ground.

The four units 1^a—1^a—1^b—1^b are identical, and a description of one will suffice for all. A unit is composed of the mixing vessel 2 (see Fig. 4) and the dissolving vessel 3, the former being open at the top and the latter substantially closed. These two vessels are connected by a relatively wide pipe 7—7 in which is interposed a valve 8, preferably of the quick opening type. As all the valves hereinafter referred to are of this type, the qualification will be understood and need not be repeated.

As illustrating the relative proportions of the various parts of this unit but not as limiting my invention to apparatus of any specific size, I will state that an apparatus consisting of four units 1^a—1^a—1^b—1^b and having a delivery capacity of from 50 to 200 gallons per minute of solution (not foam) will function properly if the mixer 2 is 15" in diameter and 15" high, the dissolving vessel 3 may be 12" in diameter and 24" high, and the connecting pipe 7 may be 3" standard pipe size.

The mixing vessel 2 has for its object to receive a previously weighed charge of the dry powdered chemical (the acid or "a" material in two of the units and the alkaline or "b" material in the other two) and to drop this charge into the dissolving vessel 3 when the valve 8 is opened. The charge is always introduced as a dry powder, but it may be dropped into 3 either in its original dry condition or it may be first brought to the consistency of a thin paste or cream by the addition of water. In the first alternative it is preferable to omit the valve 8 from the line 7 and use in its place a valve of the general construction shown in Fig. 5. This valve consists of an inverted seat 9 formed in the lower opening of pipe 7—which should in this case be enlarged to say 5" or 6" diameter—and a conical valve 10 suspended from a handle 11 which is pinned into a projection from the side of the pipe 7 as at 12. The outer end of this handle should be heavy enough to support the weight of the dry charge, which on lifting the handle (the charge being a dry and fluent powder) will immediately run en masse into the dissolving vessel 3. In this case, of course, no water is admitted into vessel 2.

In case it is preferred to convert the dry charge into a paste or cream before dropping it into vessel 3, it is desirable to place in vessel 2 the supporting plate shown at 13 in Fig. 6. This support for the powdered charge may be flat, but is preferably a spherical segment the chord of which is about one-third the diameter of vessel 2. If a plate of these proportions fails to substantially support the charge, because of unusual dryness of the powdered material, a wider or a flatter plate may be substituted. This plate is suspended in the diametric center of the vessel and a short distance from the bottom, as indicated at 13 in Fig. 6, by any convenient means such as the light rods 14. The water required for creaming the charge is introduced either over the side by means of a hand operated valve 26 and curved jet 15 (see Fig. 4) or preferably at the center as indicated at 16 in Fig. 6. The valve indicated at 16 may be so constructed that it will be opened and the water released into vessel 2 by resting on it the weight of the canister or container by means of which the charge of powder is introduced into vessel 2. Several well known types of valve are suited to this use, the particular type of valve being no part of my invention.

Whether the powdered chemical be introduced into the dissolving vessel 3 in the form of a dry powder or in the form of a cream, it immediately passes to the bottom of the vessel 3, and, as soon as vessel 2 is empty, valve 8 is closed. The chemical thus introduced into 3 will come to rest on a flat plate 17 supported near the bottom of 3 as by the studs 18. This plate should be of such size and form that it will leave a narrow annular opening 22 (say $\frac{1}{16}$ " wide in the particular size above referred to) between its edge and the inner wall of the vessel 3. The pipe 19 controlled by the valve 20 is introduced through the wall of vessel 3 at any convenient point and is carried downward therein to a short distance from the plate 17. Water entering through this pipe and projected through a narrow annular slot formed by the approach of the carefully squared end of the pipe to plate 17 will spread out to form a sheet of water moving rapidly toward the sides of vessel 3 and flowing downward over the edge of plate 17. This sheet of water will rapidly undermine and dissolve the solids resting on the plate and convert them into a clear solution which will pass downward through the annular slot 22 and out of the solution outlet 23. The rate of solution is rapid and is uniform, for any given water supply rate, until the solids are completely dissolved.

In assembling a complete apparatus as shown in Fig. 1 from four units as shown in Fig. 4, certain arrangements of the various water and solution connections are advan-

stageous as making the entire apparatus more convenient and certain in operation. Thus, the water supply (if required) for the four mixing vessels and the supply which is always required for the four dissolving vessels 5 may be drawn from a stand-pipe 35 placed centrally between the four units and continued to the hose pipe 24 which, by means of the hose coupling 25 may be attached to a 10 hose connecting the apparatus with any convenient source of water under pressure. From this standpipe the water connections 15 to each mixing vessel (each such connection being controlled by a valve 26^a—26^b) 15 are taken, and also the water connections 19^a—19^b controlled by valves 20^a—20^b to each of the dissolving vessels 3.

The solution outlet pipes 23 are each controlled by a valve 30, and these pipes are all 20 gathered into a cored manifold 29 within which, by means of channels not shown, the solutions are grouped according to their nature—that is to say, the two "a" solution outlet pipes are connected to one channel 25 terminating in a hose union 31, while the two "b" outlet pipes are similarly connected to the single hose union 32. By provisions such as these, which of course are not strictly essential to the working of the apparatus, the 30 number of outside connections may be reduced to three, viz: a single inlet connection for water, a single outlet connection for "a" solution and a single outlet connection for "b" solution. The two outlet connections are 35 intended for the attachment of individual hose lines, which for convenience may be wrapped or tied together along their length, by means of which the solutions are separately conveyed to any preferred type of mixing 40 and distributing head located in or adjacent to the seat of the fire. It is also possible to mix the solutions at a point close to the machine and convey them by a single hose line to the fire, but this is highly disadvantageous 45 because of the great reduction in volume of foam resulting from conveying it through pipes or hose at high velocity and pressure.

The four dissolving vessels 3 are each provided with a drain pipe 33 controlled by a 50 valve 34, the purpose of such pipe being to drain from the exhausted vessel the water with which it will be filled at the end of the dissolving period. These valves should also be connected together in pairs (a pair being 55 an "a" vessel and a "b" vessel).

For a unit of the size above stated a 2" pipe size water inlet and two 1½" pipe size solution outlets are proportionate to the other dimensions stated.

If the solutions are separately conveyed to and admixed at the seat of the fire it is perfectly practicable to get ten volumes of foam per unit volume of total solution used. To obtain such expansion it is desirable to make 60 the strength of the "a" solution equal to 0.6

70 pound aluminum sulfate (containing water of crystallization) per one-half gallon of water used in making such solution, and to make the strength of the "b" solution equal to 0.35 pound hydrogen sodium carbonate plus 0.05 pound dried and powdered extract of licorice per one-half gallon; a total of 1 pound total chemical to one gallon total water used. These proportions are preferred 75 proportions only, and my invention does not lie in the strength or character of solution produced except insofar as certain chemicals and general proportions are well known to be requisite to make a foam of satisfactory volume and stability.

In the operation of my apparatus the following steps are taken. A water hose is run 80 from union 25 (Fig. 1) to any adjacent supply of water under pressure, all valves—26 or 16, 8 or 10, 20, 29 and 34—being closed. The two solution outlets 31 and 32 are also 85 connected by suitable hose lines to any preferred form of mixer and distributor located at or near the fire. The apparatus is now 90 ready for use.

The chemicals required should be previously weighed out and put up in packages marked 95 respectively "a" and "b". For a solution supply of 100 gallons per minute the "a" package should contain 60 pounds of finely pulverized aluminum sulfate, dried to the point where all free water is driven off and the powder is loose and fluent but not dried so far as to drive off any appreciable proportion of the water of crystallization. The "b" 100 package should contain 35 pounds of baking soda (hydrogen sodium carbonate) and 5 pounds of extract of licorice (or other stabilizing agent) which has been previously dried and reduced to a fine powder, these two bodies being thoroughly and evenly intermixed prior to weighing. As both of the reagents named are liable to take up some water if exposed to the atmosphere and to form a crust or balls of solidified powder, the packages 105 should be of metal (ordinary slip top milk cans are suitable) and the joint should be waxed or otherwise sealed in such manner that the seal may be readily broken. A supply of such packaged chemicals should always be on hand, and if protected from the air as described will keep indefinitely.

The next step, assuming that the chemicals are to be dropped into vessel 3 as a dry powder, is to dump a charge of "a" powder 115 into one of the mixing vessels, as 2^a in Fig. 3, and a charge of the "b" powder into the opposite vessel 2^b. The valve 10 (Fig. 5) is then opened and the powder dropped into the two dissolving vessels 3^a and 3^b, after 120 which valve 10 is closed.

If the powders are to be passed into the dissolving vessels 3 as a cream, two valves 20^a and 20^b are opened, and just prior to dumping in the powders the two valves 26^a and 26^b 130

are opened, the streams of water from these valves carrying the powder instantly into the vessels 3^a and 3^b. Or if the arrangement shown in Fig. 6 is used, the weight of the canister will automatically open valve 16 and flush the powder into vessel 3 at the instant of dumping. In either case the valves 20^a and 20^b are closed as soon as the powder has passed down into vessels 3^a and 3^b.

10 The valves 30^a and 30^b (one pair only) are then opened, and thereafter the valves 20^a and 20^b, the latter admitting water into vessels 3^a and 3^b and forcing the *a* and *b* solutions out of outlets 31 and 32 through the 15 corresponding hose lines to the mixing head where they are intermixed and produce the desired foam.

While the first pair of dissolving vessels are being discharged the second pair are being charged with chemicals (either dry or in the form of a cream) and are thus ready to deliver solution on closing the first pair of solution valves 30^a and 30^b and opening the opposite pair, and opening the second pair of water valves 20^a and 20^b. If the four 30 valves were replaced by check valves the necessity for reversing these valves would be avoided, as their sole purpose is to prevent solutions leaving one pair of dissolving vessels 3 under pressure from flowing back into the opposite pair.

When discharge of the first pair of vessels 3 is completed the two drain valves 34 on such vessels should be momentarily opened 35 to allow any water remaining in such vessels to run out.

The above said charges of chemicals, used at a rate of 100 gallons total output of solution per minute, equivalent to a foam production of substantially 1000 gallons per minute, will suffice for two minutes operation, allowing the same period of time for the simple operations of draining the mixing vessels, dumping in the dry charges, flushing them through or allowing them to run through into vessels 3, and closing the two valves 20. It therefore requires no undue haste on the part of a single operator to keep this apparatus delivering foam continuously if the operator be kept supplied with the packaged chemicals within easy reach.

I claim as my invention—

1. An apparatus for producing a fire-foam solution, comprising: a hopper for receiving 55 a supply of a soluble powder; a substantially closed vessel in fixed position beneath said hopper; means for downwardly directing a jet of water into said hopper and for intermixing said water with said powder to the 60 consistency of a fluent mass; a means of communication between said hopper and said vessel; a controllable closure within said communication means for permitting said fluent mass to pass at will into said vessel; means 65 for admitting water into said vessel under

pressure in a flow-stream; means for intermixing said fluent mass with said flow-stream and for producing aqueous solution of the powder therein contained, and means for conveying said solution to a point of use thereof, the conveyance of said solution to said point of use being brought about solely by the pressure of the entering water.

2. An apparatus as and for the purpose described in claim 1, in which the means for intermixing water with powder to the consistency of a fluent mass consists of a plate fixed in a position above the bottom of the hopper, for partially supporting a mass of dry powder, and means for projecting a jet of water, at relatively high velocity, toward said plate, in such manner as to wash said powder under conditions of turbulence to a position below said plate.

In witness that I claim the foregoing I have hereunto subscribed my name this 14th day of September, 1927.
